ELECTRONIC FLASH ADAPTER FOR CAMERAS

Keisuke Kitagawa, Tokyo, Japan, assignor to
Kalimar, Inc., St. Louis, Mo.

Filed June 25, 1971, Ser. No. 157,079

Term of patent 7 years

Int. Cl. D16—05
U.S. Cl. D61—1 F

FIG. 1

FIG. 4

FIG. 2

FIG. 5

FIG. 3

FIG. 6

FIG. 1 is a top plan view of an electronic flash adapter for cameras showing my new design.

FIG. 2 is a front elevational view taken from the lower side of FIG. 1.

FIG. 3 is a bottom plan view thereof.

FIG. 4 is a side elevational view taken from the right hand side of FIG. 2.

FIG. 5 is a rear elevational view thereof.

FIG. 6 is a side elevational view taken on the left hand side of FIG. 2.

I claim:

The ornamental design for an electronic flash adapter for cameras, as shown.
